UNITED STATES PATENT OFFICE.

CHARLES N. COON AND JOHN CANTLON, OF MATTOON, ILLINOIS.

VALVE.

990,111.

Specification of Letters Patent. Patented Apr. 18, 1911.

Application filed August 1, 1910. Serial No. 574,800.

To all whom it may concern:

Be it known that we, CHARLES N. COON and JOHN CANTLON, citizens of the United States, residing at Mattoon, in the county of Coles and State of Illinois, have invented 5 certain new and useful Improvements in Valves; and we do declare the following to be a full, clear, and exact description of the invention, such as will enable others skilled 10 in the art to which it appertains to make and use the same.

This invention relates to improvements in globe valves.

One object of the invention is to provide 15 a valve of this character having a double faced valve seat and a valve adapted to be reversed whereby when one side of the same and one face of the seat become worn to such an extent as to impair their usefulness, 20 the valve may be reversed to engage the unused face of the seat thereby greatly increasing the life and usefulness of the valve.

Another object is to provide means whereby the valve may be held in an open position 25 when desired.

With the foregoing and other objects in view, the invention consists of certain novel features of construction combination and arrangement of parts as will be more fully 30 described and particularly pointed out in the appended claims.

In the accompanying drawings: Figure 1 is a vertical longitudinal sectional view of a valve constructed in accordance with the invention, and showing the valve arranged in 35 one position. Fig. 2 is a similar view showing the valve arranged in its reverse position; and, Fig. 3 is a detail sectional view of the valve removed from the casing.

40 In the present instance the invention is shown in the form of a globe valve comprising a casing 1, which may be of the usual or any desired shape and in which is formed the usual partition 2. In the partition 2 is 45 formed a threaded passage 3, in which is screwed a tubular valve seat 4, the upper edge of which projects above the partition 2 and is flanged to form a shoulder 5, which engages the upper side of the partition as 50 shown. The upper edge of the seat 4 is beveled or inclined on its inner and outer sides to form inner and outer valve receiving faces 6 and 7.

55 On the upper side of the valve casing is formed an upwardly projecting tubular extension 8, which is threaded on the outer

surface of its upper end and is adapted to receive a hood 9 into which the stem of the valve projects as will be hereinafter described. The hood 9 is provided with a 60 flared lower end which provides a seat 10 for a nut 11 which is engaged with said seat and with the upper end of the tubular extension 8 of the valve casing. The lower end of the hood 9 is provided with an annular flange 12 with which is engaged a cap nut 13, said nut having a screw threaded engagement with the extension 8 whereby said hood is securely clamped to the valve casing. The nut 11 has a tapered upper side which 70 fits into the flared lower end of the hood and is beveled on its lower edge to fit in the beveled upper end of the extension 8, said end being thus securely held in place.

In the extension 8 of the valve casing and 75 in the hood 9 is a two part valve stem, the lower section 14 of which is threaded for a portion of its length and is provided on its lower end with a squared head 15 in which is formed a transverse T shaped slot 16 by 80 means of which the stem is connected to the valve in the manner hereinafter described. The threads of the portion 14 of the stem are inclined on their lower sides only and engage similarly formed threads in the nut 85 11. By forming the threads on the stem and in the nut in this manner the square or flat upper portion of the thread will receive the thrust of the valve.

The upper portion of the lower section of 90 the valve stem is squared, as shown at 17, and is engaged with a squared socket 18 formed in the lower portion of the upper section 19 of the valve stem. The upper portion 19 of the valve stem is of less diameter than the lower portion 18 and thereby forms a shoulder, the width of which is increased by an annular flange 20 formed on the upper edge of the portion 18 of the stem as shown. On the flanged and shouldered 100 upper end of the lower portion 18 of the stem is formed one member of a ball race, the opposite member of which is formed on the lower side of a packing ring 21 which is arranged on the reduced portion 19 of the stem. In the ball race thus formed is arranged an annular series of bearing balls 22 whereby an anti-frictional engagement is provided between the packing ring 21 and the valve stem. On the threaded upper end 105 of the hood 9 is screwed a packing nut or gland 23 in which is arranged a suitable

packing 24 whereby a fluid tight joint is provided for the valve stem. The upper end of the stem is squared to receive any suitable form of wrench or handle.

- 5 Secured to the lower end of the valve stem and adapted to be engaged with the valve seat 4 is a reversible valve 25 comprising a cylindrical body portion 26 having in one side a circular recess 27 the side walls of
- 10 which are beveled or inclined as shown. On the opposite side of the body portion 26 is formed a tapered projection 28 which, when the valve is arranged in the position shown in Fig. 1, is adapted to engage the inner face
- 15 6 of the valve seat when the valve is in closed position. When the valve is in the position shown in Fig. 2 of the drawings and is closed, the tapered or inclined walls of the recess 27 will engage the outer beveled face
- 20 7 of the seat. On the opposite sides of the valve are formed T shaped lugs 29 which are adapted to engage the T shaped slot 16 in the head 15 on the lower end of the valve stem thereby securing the valve to the stem
- 25 in either of its positions. By thus forming the valve and seat it will be readily seen that the valve may be quickly reversed when one side or the other has become worn, thus presenting a new or unworn working surface
- 30 for engagement with the unused face of the valve seat. It will also be readily seen that by screwing the lower portion 14 of the stem through the nut 4 that the valve may be adjusted and held in an open or closed position.

From the foregoing description taken in connection with the accompanying drawings, the construction and operation of the invention will be readily understood without

- 40 requiring a more extended explanation.
- Various changes in the form, proportion and the minor details of construction may be resorted to without departing from the principle or sacrificing any of the advantages of the invention as defined in the appended claims.

Having thus described our invention what we claim is:

1. In a valve of the character described, a
- 50 casing, a hood having a detachable engage-

ment with said casing, a tubular valve seat removably secured in said casing, said seat having inner and outer valve receiving faces, a valve having on one side a tapered projection adapted to be engaged with the inner face of said seat when in one position and having on its opposite side a tapered recess adapted to engage the outer face of said seat when in another position, T shaped lugs formed on the opposite sides of said valve, a two section valve stem arranged in said hood and casing, means whereby the sections of said stem are movably connected together, means whereby the lower end of the stem is adapted to be detachably connected to the valve in either of its positions, a nut secured between said hood and valve casing, threads formed on the lower section of the valve stem whereby said section has a movable engagement with said nut, said threads having an inclination on their lower sides and having flat upper sides, a packing nut arranged on the upper end of said hood, a packing ring arranged in said nut, and an anti-frictional bearing arranged between said packing ring and the upper section of the valve stem.

2. In a valve of the character described, the combination of a casing, a tubular valve seat removably secured in said casing, said seat having inner and outer valve seating faces, a valve having on one side a tapered projection adapted to be engaged with the inner face of said seat when in one position and having on its opposite side a tapered recess adapted to engage the outer face of said seat when in another position, T-shaped lugs formed on the opposite sides of said valve, a valve stem having a slot in its lower end to engage either of said lugs, and means for operating said stem.

In testimony whereof we have hereunto set our hands in presence of two subscribing witnesses.

CHARLES N. COON.
JOHN CANTLON.
